(57) **CLAIM**

The ornamental design for a display screen or portion thereof with animated graphical user interface, as shown and described.

DESCRIPTION

FIG. 1 is a front view of a first image in a sequence for a display screen or portion thereof with animated graphical user interface showing my new design;

FIG. 2 is a second image thereof;

FIG. 3 is a second embodiment thereof, showing a front view of a first image in a sequence for a display screen or portion thereof with animated graphical user interface showing my new design;

FIG. 4 is a second image thereof;

FIG. 5 is a third embodiment thereof, showing a front view of a first image in a sequence for a display screen or portion thereof with animated graphical user interface showing my new design;

FIG. 6 is a second image thereof; and

FIG. 7 is a fourth embodiment thereof, showing a front view of a first image in a sequence for a display screen or portion thereof with animated graphical user interface showing my new design; and,

FIG. 8 is a second image thereof.

The outermost broken lines in the figures show a display screen or portion thereof, and form no part of the claimed design. The other broken lines in the figures show portions of the animated graphical user interface that form no part of the claimed design.

The appearance of the animated image sequentially transitions between the images shown in FIGS. 1-2, between the images shown in FIGS. 3-4, between the images shown in FIGS. 5-6, and between the images shown in FIGS. 7-8. The
